UNITED STATES PATENT OFFICE.

RAYMOND E. MCKEE, OF CHICAGO, ILLINOIS.

DESIGN FOR A ROPE-CLAMP.

46,287.

Specification for Design.

Patented Aug. 18, 1914.

Application filed April 30, 1914. Serial No. 835,540. Term of patent 3½ years.

To all whom it may concern:

Be it known that I, RAYMOND E. MCKEE, a citizen of the United States, residing at Chicago, in the county of Cook and State of Illinois, have invented a new, original, and ornamental Design for a Rope-Clamp, of which the following is a specification, reference being had to the accompanying drawing, forming part thereof.

The figures illustrate my rope clamp showing my design.

The Figures 1 and 3 illustrate side views of rope clamp. Fig. 2 illustrates a front view and Fig. 4 a plan view.

I claim:

The ornamental design for a rope clamp, as shown.

RAYMOND E. MCKEE.
